UNITED STATES PATENT OFFICE.

ERASTUS ROADIFER, OF LOGAN, IOWA, ASSIGNOR OF ONE-HALF TO ROY E. ADAMS, OF LOGAN, IOWA.

FOLDING CRATE.

No. 893,752.

Specification of Letters Patent.

Patented July 21, 1908.

Application filed August 22, 1907. Serial No. 389,719.

To all whom it may concern:

Be it known that I, ERASTUS ROADIFER, a citizen of the United States, residing at Logan, in the county of Harrison and State of Iowa, have invented certain new and useful Improvements in Folding Crates; and I do declare the following to be a full, clear, and exact description of the invention, such as will enable others skilled in the art to which it appertains to make and use the same.

This invention relates to an improved folding crate, and the object thereof is to provide a crate which is simple in construction and cheap to manufacture, and which when folded may be locked in such position and handled as one piece.

Figure 1 of the accompanying drawings represents a perspective view of the crate in set-up or operative position; Fig. 2 represents a top plan view of the crate in folded position; Fig. 3 represents a longitudinal section taken on line 3—3 of Fig. 2; Fig. 4 represents a transverse section of a crate taken on line 4—4 of Fig. 2.

In the embodiment illustrated the invention is shown applied to a poultry crate constructed of the ordinary longitudinal slatted members, and which comprises a bottom 1 having end members 2 and 3 hinged to fold inwardly flat against its upper face. Side members 4 and 5 are hinged to the opposite sides of said bottom member 1 to fold outwardly, and at the upper ends of these side members is hingedly connected the top member 8. These side members 4 and 5 are divided longitudinally intermediately of their ends into sections 6 and 7 hingedly connected to each other to fold outwardly. The top member 8 has a sliding slat 9 arranged to slide in guides formed in any suitable manner. This slat is provided at its opposite ends with turn-buttons 10 and 11 which are adapted to be turned down against the end members to hold the slide against movement in either direction. When it is desired to open this slide for the insertion or removal of a fowl or other object, one of the turn-buttons is turned up and the slide moved outwardly.

Fasteners 12 and 13 are arranged at oppo-

site sides of the end members to engage the folding side members and hold said members rigidly together. These fasteners are preferably made in the form of hooks, as 14, which engage eyes, as 15, screwed into said side members. A hook 18 is also placed at each end of the top to engage eyes in the end members, and a revoluble keeper 16 is provided for locking this hook in closed position. A foldable partition 20 is pivotally connected at its upper end with the inner face of the top member 8 and adapted to fold flat thereagainst when the crate is collapsed. A spring-hook 21 is attached to the lower edge of said partition to hold it in operative position when the crate is set up.

When the side members 4 and 5 are raised to perpendicular position they carry the top member 8, which is hinged thereto, into its proper position, and the ends 2 and 3 are then opened up and fastened to said side and top members, whereby the crate is rigidly held in operative position.

When it is desired to fold the crate, the fasteners 12, 13 and 18 are disconnected and the end members 2 and 3 folded inwardly on the bottom 1, and the side members 4 and 5 are then bent outwardly and the sections of each folded flat against each other with the top resting on the folded end members. The hook 16 is then connected with an eye 17 on the bottom member, whereby the parts are securely held in folded position.

While in the form illustrated the side members are described as made in hingedly connected folding sections, it is to be understood that the end members may be so made instead of side members if desired, and the side members constructed like the end members herein shown.

I claim as my invention:—

A folding crate comprising a top member, a bottom member, a pair of side members each hinged to said top and bottom members, each of said side members being divided longitudinally and connected by centrally attached hinges, end members hinged to said bottom member and folded inwardly and provided with means for fastening them to

the top and side members, a partition hinged to the top member, and yieldable means carried by the bottom of said partition for detachably engaging the bottom, said partition adapted to fold flat against the top when desired.

In testimony whereof I have hereunto set

my hand in presence of two subscribing witnesses.

ERASTUS ROADIFER.
